UNITED STATES PATENT OFFICE.

MARTIN ANDREWS, OF CHICAGO, ILLINOIS, ASSIGNOR TO PHOENIX FIRE
EXTINGUISHER CO., OF CHICAGO, ILLINOIS, A CORPORATION.

VALVE FOR AUTOMATIC FIRE-EXTINGUISHERS.

No. 841,915.

Specification of Letters Patent.

Patented Jan. 22, 1907.

Application filed June 5, 1906. Serial No. 820,259.

To all whom it may concern:

Be it known that I, MARTIN ANDREWS, a citizen of the United States, residing in Chicago, in the county of Cook and State of Illinois, have invented certain new and useful Improvements in Valves for Automatic Fire-Extinguishers, of which the following is a specification.

The invention relates more particularly to an indicator for use in connection with the valve device than to the valve device itself, and here it may be stated that the invention is not limited to a valve device of any particular type or construction, although it is especially well adapted for that class of dry-pipe valve devices in which a temporary valve-holding device is used for holding the water-valve or the air-valve, or both the water-valve and the air-valve, seated while the system is being charged with air under pressure and until the pressure becomes sufficient to hold the valve seated, after which the temporary valve-holding device is tripped, leaving the valve under the control of the air-pressure in the distributing system. In some valve devices of this class the temporary holding device is tripped manually, while in others it is tripped automatically by the pressure in the system when said pressure reaches a predetermined amount. The invention is applicable to valve devices of both these types; but it is particularly applicable to the type having a temporary valve-holding device which is tripped automatically, and hence this type is selected for the purposes of illustration and description.

The object of the invention is to provide means for positively and with absolute certainty indicating not only the facts that the valve is set and that the temporary valve-holding device has been tripped so as to relieve the valve of its restraint and leave it under the control of the system pressure when these conditions actually exist, but also for as positively and with as absolute certainty preventing a false indication that the valve has been set or that it has been relieved of the restraint of the temporary valve-holding device when these conditions do not, in fact, exist.

I am aware that it has been proposed to provide devices intended to automatically indicate that the valve is "set" and that it

has been relieved of the restraint of the temporary valve-holding device; but in all such devices of which I am aware these facts are not indicated positively and with absolute certainty; but, on the contrary, they may be at variance with the readings of the indicator.

The invention consists in the features of novelty that are hereinafter described with reference to the accompanying drawings, in which—

Figure 1 is a vertical section of a valve for automatic fire-extinguishers having an indicator embodying the invention, the cutting planes being approximately indicated by the lines $z z$ and $y y$, Fig. 2. Figs. 2 and 3 are vertical sections thereof in a plane approximately indicated by the line $z z$, Fig. 1, showing the parts in different positions. Fig. 4 is a horizontal section showing a detail.

The valve shown in the drawings has a casting A, providing a chamber A', an opening A" for the admission of water from any suitable source of supply, and an opening A², through which the chamber is in constant open communication with the riser of the distributing system. Neither the riser nor the distributing-pipes is shown, as they are well understood by those skilled in the art. It will be understood that normally they are charged with air under pressure, and by reason of the open communication with the chamber A' the air in the latter will be under the same pressure.

The water-inlet is controlled by a valve B, carried by a swinging arm or link b, and the valve is normally held seated by mechanism controlled by the pressure in the system hereinafter called the "main valve-holding device." The present invention is not concerned with the details in the construction of this main valve-holding device; but for the sake of completeness the construction shown in the drawings will be briefly described.

The valve B is engaged by the lower end of one member C of a two-part strut, the upper end of said member C being in engagement with the lower end of the other member D of said strut, while the upper end of the latter engages a spider E. The two members of the strut have rocking engagement with each other and with the valve and spider, respectively, and form a toggle by which the valve

is held seated so long as its members are in approximate alinement. Loops *d*, carried by the member *D* and encircling lateral projections *c* on the member *C*, prevent the latter 5 from falling completely away from the former, and links *d'*, suspended from the spider *E*, support the member *D* when the toggle buckles.

An arm *D'* projects laterally from the 10 member *D* and forms the long arm of a bell-crank lever, the short arm of which is formed by the member *D*. From the arm *D'* is suspended a weight *F*, the tendency of which is to depress the arm and buckle the valve-holding strut. To the arm is connected an 15 air-valve *G*, adapted to an annular seat *H*, providing a chamber *h*, the air in which is maintained at a low or atmospheric pressure through an opening *h'*.

20 When the valve is set and the pressure in the system is normal, the upward pressure of the air against the air-valve will hold it seated and hold the weight *F* elevated. While seated the air-valve will hold the arm *D'* in 25 elevated position, and said arm in turn will hold the members of the valve-holding strut in approximate alinement, whereby the water-valve is held seated in opposition to the pressure of the water against its under side. 30 Upon a reduction of the air-pressure to a predetermined amount the weight will overcome the pressure upon the air-valve and will fall and in doing so will draw down the arm *D'*, buckle the valve-holding strut, and permit 35 the water-valve to unseat.

In order to hold the water-valve and air-valve to their respective seats while the system is being charged with air under pressure, a temporary valve-holding device is provided. 40 As shown in the drawings, this temporary valve-holding device consists of a displaceable part or bridge *I*, hinged to the casing at *i*, a vertically-adjustable post *I'*, carried by the bridge and engaging the arm *D'* of the 45 main valve-holding device, and a movable part *J*, hereinafter called a "trigger," which is adapted to engage the free end of the bridge *I* and when in engagement therewith hold the bridge in such position that its post *I'* 50 engages the arm *D'* of the main valve-holding device, and thereby holds the air and water valves seated while the system is being charged. The part *J* forms a part of the temporary valve-holding device, in that it holds 55 a displaceable part *I* in place so long as it is in engagement with it, and it also has the function of a trigger, in that when disengaged from the displaceable part *I* it permits the latter to fall away, thus relieving the main 60 valve-holding device of its restraint and leaving the latter under the sole control of the pressure in the system. As shown in the drawings, the trigger *J* consists of an endwise-movable rod or stem extending through the

hollow shank *k* of a diaphragm-box *K*, which shank is screwed into a threaded opening in the casing. The box *K* is made of two dished parts, having marginal flanges secured together by bolts, the flexible diaphragm *L* being clamped between them in customary manner. The diaphragm is connected to the trigger so that each partakes of the movement of the other. One side of the diaphragm is exposed to the system pressure through the hollow shank *k*, and the other side is exposed 70 to the atmospheric pressure through an opening in the outer part of the box *K*. A spring *M* exerts its pressure in one direction against the box and in the other direction against the trigger with a tendency to project its inner 75 end into position to engage the bridge.

In order to set the parts in the positions in which they are shown in Figs. 1 and 2, the face-plate *a* of the casing is removed. When replaced, it closes the chamber of the casing 80 air-tight, and the system is charged with air under pressure. The pressure thus produced acting upon the diaphragm *L* will when a predetermined amount is reached withdraw the trigger from engagement with the bridge *I* and permit it to fall to the position indicated by dotted lines in Fig. 3. For the purpose of indicating that this action has taken place it has been proposed to place an inscription (the word "Set") on a portion *j* of the trigger, which extends loosely through the aforesaid opening in the box *K*, so that as the trigger gradually moves outward under the influence of the pressure upon the diaphragm this inscription will gradually come into view. 90 This is open to the objection that in every instance the inscription, or more or less of it, comes into view before the trigger has actually disengaged the bridge, and in no instance does it positively indicate that the bridge 95 has actually fallen. At best it indicates simply that the trigger has reached a position that will permit the bridge to fall; but the fact that it has fallen is left to be assumed from the fact that the inscription is visible. 100 To overcome this objection, I provide an indicator which is so controlled by a displaceable part—*e. g.*, the bridge—interposed between the trigger and the main valve-holding device that the inscription cannot be displayed until said part is actually displaced. 105

N represents an air-tight box having a threaded shank *n* screwed into a threaded opening through the top of the casing *A*, said shank having through it an opening placing its interior in communication with the interior of the casing. The opening is non-circular, and through it passes a non-circular rod *O*, the lower end of which is adapted to engage and be supported by the bridge *I* when the latter is in operative position. The upper portion of the rod occupies the box *N* and carries a target *P*, bearing an inscription— 110 115 120 125

e. g., the word "Set." The front of the box has through it an opening n' , over which a heavy pane of glass Q is secured by a clamping-frame R, fastened to the box by screws or bolts. The downward movement of the rod is limited by a shoulder provided by a pin o, passing through the rod and adapted to come in contact with the bottom of the box. When the rod is in its lowermost position, the inscription on the target will be visible through the opening n' ; but it will be seen that the rod cannot come to this position until relieved of support by the bridge I. The instant the bridge falls the rod will fall by gravity and by a quick movement bring the inscription into view. Hence should the bridge from any cause fail to fall after being released by the trigger the indicator will be prevented from operating, and thus the giving of a false indication is positively prevented. It will be seen also that when in set position the indicator has a part—e. g., the lower end of rod O—which lies in the path in which the bridge moves in coming into operative position, so that it cannot reach this position until the indicator has been moved to a position which indicates that the bridge is in place. In other words, the temporary valve-holding device and the indicator have engaging parts movable in a common path, whereby each until displaced interferes with the movement of the other.

While I have shown and described a gravity-operated indicator, it is manifest that a spring-operated indicator is within the scope of the invention, generically considered, the characteristic feature of which is the indicator controlled by a displaceable part of the temporary valve-holding device.

40 What I claim as new, and desire to secure by Letters Patent, is—

1. In a device of the class described, the combination with a valve and a main valve-holding device, of a temporary valve-holding device, means for tripping it, and an indicator, the temporary valve-holding device and indicator having parts movable in a common path whereby each, until displaced, interferes with the movement of the other, substantially as described.

2. In a device of the class described, the combination with a valve and a main valve-holding device, of a temporary valve-holding device, means for tripping it, and an indicator, the temporary valve-holding device having a part occupying a path in which a part of the indicator moves in setting the indicator, substantially as described.

3. In a device of the class described, the combination with a valve and a main valve-holding device, of a temporary valve-holding device having a trigger and a displaceable part interposed between the trigger and the main valve-holding device, means for trip-

ping the trigger and releasing said displaceable part, and an indicator controlled by said displaceable part, substantially as described. 65

4. In a device of the class described, the combination with a valve and a main valve-holding device, of a temporary valve-holding device, means for tripping it, and a quick-acting indicator controlled by the temporary valve-holding device, substantially as described. 70

5. In a device of the class described, the combination with a valve and a main valve-holding device, of a temporary valve-holding device, means for tripping it, and a gravity-operating indicator controlled by the temporary valve-holding device, substantially as described. 75 80

6. In a device of the class described, the combination with a valve and a main valve-holding device, of a temporary valve-holding device, means for tripping it, and an indicator controlled by the temporary valve-holding device, said indicator having a movable part adapted to fall by gravity when released, substantially as described. 85

7. In a device of the class described, the combination with a valve and a main valve-holding device of a temporary valve-holding device having a displaceable part and a trigger for holding it in operative position, means for tripping the trigger, and an indicator having a part controlled by said displaceable part, substantially as described. 90 95

8. In a device of the class described, the combination with a valve and a main valve-holding device, of a temporary valve-holding device having a displaceable part and a trigger for holding it in operative position, means for tripping the trigger and an indicator having a part engaged and controlled by said displaceable part and adapted to fall by gravity when released, substantially as described. 100 105

9. In a device of the class described, the combination with a valve and a main valve-holding device, of a temporary valve-holding device, means for tripping it, and an indicator having a vertically-movable rod engaged by a movable part of the temporary valve-holding device and adapted to fall by gravity when released, substantially as described. 110

10. In a device of the class described the combination with a valve and a main valve-holding device, of a temporary valve-holding device, means for tripping it, and an indicator controlled by the temporary valve-holding device, of an air-tight enclosure containing the valve, valve-holding devices and indicator, substantially as described. 115 120

11. In a device of the class described, the combination with a valve, a main valve-holding device, and an air-tight casing containing them, of a temporary valve-holding device, means for tripping it and an indicator controlled by the temporary valve-holding de- 125

vice, said indicator having a target and an air-tight box containing the target, said box having internal communication with the interior of the casing, and having a transparent pane, substantially as described.

12. In a device of the class described, the combination with a valve and a main valve-holding device, of a temporary valve-holding device having a trigger and a displaceable

part interposed between the trigger and the main valve-holding device, means controlled by the pressure in the system for tripping the trigger, and an indicator controlled by said displaceable part, substantially as described.
